UNITED STATES PATENT OFFICE.

JOHN W. EVILSIZER, OF IANTHA, MISSOURI.

MORTISING-MACHINE.

1,305,269.

Specification of Letters Patent. Patented June 3, 1919.

Application filed February 2, 1917. Serial No. 146,139.

To all whom it may concern:

Be it known that I, JOHN W. EVILSIZER, a citizen of the United States, residing at Iantha, in the county of Barton, State of Missouri, have invented a new and useful Mortising-Machine; and I do hereby declare the following to be a full, clear, and exact description of the invention, such as will enable others skilled in the art to which it appertains to make and use the same.

This invention relates to the art of wood working, and more especially to a simple, improved and practical mortising machine, and an object of the invention is to provide 15 an oscillatory mortising tool and support therefor, whereby a piece of timber may be mortised.

Another object of the invention is the provision of means mounted in guides to be reciprocated, and provided with means for holding a piece of timber, whereby the timber may be brought into engagement with the mortising tool.

A further object of the invention is to provide means for holding the reciprocating means normally in a raised position.

In practical fields the details of construction may necessitate alterations falling within the scope of what is claimed.

30 The invention comprises further features and combination of parts, as hereinafter set forth, shown in the drawings and claimed.

In the drawings:

Figure 1 is a view in side elevation of the 35 improved machine constructed in accordance with the invention.

Fig. 2 is a plan view of the machine.

Fig. 3 is a vertical sectional view on line 3—3 of Fig. 1.

40 Fig. 4 is a detail perspective view of the oscillatory mortising tool.

Fig. 5 is a view in rear elevation of the mortising tool.

Referring more especially to the drawings, 1 designates a stand or pedestal having a base 2, which may be secured in any suitable manner to the floor or the like, and mounted upon the stand or pedestal is a bed plate 3. Secured by bolts 4 upon the bed 45 plate is a supporting bracket 5 provided with a reduced upper end 6. An oscillatory tool holder 7 is provided, and which comprises a substantially circular head 8 and an elongated arm 9. The rear face of the head 8 is provided with a segmental recess 10 for the reception of the reduced end 6 of the

supporting bracket, there being a pin 11 extending through the reduced end 6 and the head 8, to pivotally mount the tool holder, whereby the same may be oscillated. The 60 peripheral edge of the head 8 is provided with a plurality of angular recesses 12, in which the cutting tools 13 are detachably secured by the screws 14. It is to be noted that the tools are so arranged on the head of 65 the holder, as to gouge or cut a segmental mortise opening in a piece of timber, when the timber is brought in contact with the tools, provided however, the holder penetrates the timber as far as the pivot of the 70 holder. However, should the timber be wide enough to permit the holder to enter the same beyond the pivot, the timber will be provided with a mortise having parallel side 75 edge walls, which are connected by a segmental arch wall. Should the piece of timber be narrow enough to permit the tool holder to cut through, a rectangular mortise opening would be provided. The bed plate is provided with an opening 16, and downwardly extending arms 17, which project downwardly from the bed plate adjacent the ends of the opening 16. The inner faces of the arms 17 have guide ribs 18, which are engaged by the guide grooves 19 of the longitudinal opposite edges of the vertically reciprocating carriage 20. The upper end of the carriage 20 is provided with a timber holding member 21 provided with the lugs 22 to penetrate the piece of timber, as shown 90 at 23, in order to hold the same in place. Projecting laterally from one face of the timber holding member 21 are the arms 24, which receive the timber clamps or rods 25, there being hand nuts 26 threaded upon the 95 clamps or rods 25, for holding the right angle extending ends 27 tight against the under surface of the piece of timber, to securely hold the same in place while being mortised. A coil spring 28 is provided, and 100 has one end connected to a screw 29 of the lower end of the carriage, and its other end connected at 30 to the under face of the bed plate, thereby holding the carriage normally in a raised position, there being a pin 31 105 carried by the carriage to engage the under face of the bed plate to limit the carriage to its uppermost position. Pivoted upon an arm 32 as at 33 is a lever 34, one end of which is provided with a roller 35 to engage 110 under the bed plate. By grasping the handle end of the lever 34 and moving the same

downwardly, the carriage may be moved downwardly, to bring the piece of timber in contact with the tools of the oscillating tool holder, and as pressure is maintained upon the lever 34, a mortise opening will be cut through the piece of timber. Mounted in suitable bearings 36 of the bed plate is a shaft 37, having a disk wheel 38 on one end, and idle and fast pulleys 39 and 40 upon the other end. Connected eccentrically at 41 to the disk wheel is a pitman rod 42, the other end of which is pivotally mounted upon a reduced end 43 of the pin 44, the larger portion 45 of which extends through the segmental slot 46, in order to guide the tool holder and its arm in their oscillatory movements. The reduced portion 47 of the pin 44 passes through the lower part of the arm 9 of the tool holder, so that the arm will pivot upon the pin. The pin 44 is provided with nuts 48 and 49 upon both ends, thereby holding the pin in engagement with the slot 46 and the pitman in position. The usual form of belt shifting device 50 is mounted in bearings of the bed plate for shifting the belt 51 from the idle pulley to the fast pulley and vice versa, so as to impart movement to the shaft 37, which, owing to the disk wheel and pitman, imparts an oscillatory movement to the tool holder. The belt 51 may receive power from any suitable source not shown.

The invention having been set forth, what is claimed as new and useful is:

35 1. In a mortising machine, a bed frame having a guide, a carriage reciprocating in said guide and having a work holder at its

upper end, said work holder comprising a timber holding member extending transversely of the upper end of the carriage and 40 provided with lugs to penetrate the piece of timber to be held, said timber holding member having upwardly extending arms, a pair of screws mounted in said arms and having at their forward portions downwardly right 45 angle extending parts terminating in inwardly extending lugs, and means threaded on the screws to draw the right angle extending parts and lugs against the forward and underface portions respectively of the 50 piece of timber, whereby the first lugs are held in penetrating contact with the timber.

2. In a mortising machine, a bed frame, an upstanding bracket thereon having on its upper edge a projection, a mortising tool 55 having one face chambered out to receive said restricted projection, the opposing walls of the chambered out portion adapted to cooperate with said projection to limit the tool in its oscillatory movement, means to pivot 60 the tool to the projection, said bracket having an arcuate slot concentric with the pivot of the tool, the lower end of the tool having means engaging in said slot for guiding the tool, and a reciprocating member connected 65 to said last named means to oscillate the tool.

In testimony whereof I have signed my name to this specification in the presence of two subscribing witnesses.

JOHN W. EVILSIZER.
